UNITED STATES PATENT OFFICE.

ABEL GUILONNEAU, OF DENVER, COLORADO.

ORE-CONCENTRATOR.

No. 867,267.

Specification of Letters Patent.

Patented Oct. 1, 1907.

Application filed April 29, 1907. Serial No. 370,835.

To all whom it may concern:

Be it known that I, ABEL GUILONNEAU, a citizen of the United States, residing at Denver, in the county of Denver and State of Colorado, have invented new and 5 useful Improvements in Ore-Concentrators, of which the following is a specification.

This invention relates to ore concentrators, the object of the invention being to provide an effective apparatus of this character for quickly concentrating ores of 10 different kinds supplied thereto.

A concentrator involving my invention possesses other advantageous features which, with the foregoing, will be fully treated in the following description of that form of embodiment of the apparatus which I have selected for illustration in the accompanying drawings forming part of this specification. The novelty of the invention will be covered in the claims succeeding said description.

Referring to said drawings: Figure 1 is a top plan 20 view of a concentrator involving my invention, with a portion of the belt broken away. Fig. 2 is a rear elevation of the concentrator with the head motion removed. Fig. 3 is a sectional side elevation of the same, the belt being in section. Fig. 4 is a detail view in front elevation of the belt. Fig. 5 is a top plan view of the same, and Fig. 6 is a sectional detail of said belt. Figs. 7 and 8 are detail views of the adjusting gear.

Like characters refer to like parts throughout the several figures.

30 The apparatus includes in its make-up a suitable bed or foundation and this may be of any desirable character, the same comprising in the present instance the suitably connected duplicate sills 2 to the opposite ends of which are fastened in some convenient way the 35 flexible links or straps 3 of which there are four illustrated in the drawings. The upper ends of these links are connected in some desirable manner to the connected frame members 4 which directly sustain the concentrating mechanism and which are simultaneously 40 given a vibratory movement in a direction transverse of the endless belt hereinafter described for the purpose of stratifying the pulp on said belt. The links 3 may be of wood or metal or a composition of these materials. The frame members 4 are separated horizontally 45 tally from the sills 2, as shown clearly in Fig. 2.

A roller or drum is shown at 5, and the shaft 6 of said roller is supported by suitable bearings upon the frame members or beams 4, said shaft 6 having fixed thereto at one end, as shown in Fig. 1, the disk 7 having on 50 its outer face a lug as 8, the function of which will be hereinafter described. This shaft 6 serves as a pivot or center for the beams 9, said beams 9 having at the end thereof opposite the shaft 6 bearings for the drum or roller 10 which is complementary to the drum 5. An 55 endless belt as 11 travels around these two drums. The belt 11, or at least the working portion thereof, is

inclined; and, in the present case, the upper run of said belt constitutes the working portion thereof. The inclined belt may be made of any suitable material. I prefer, however, to make it of rubber and, when of 60 rubber, it will have molded thereon the transversely disposed riffles 12 which extend from the back of the belt or that part at the right in Fig. 3, to the front thereof. When the belt is of rubber I prefer to make the riffles 12 of rubber, the said riffles being of progressively 65 decreasing thickness or depth from the back of the belt to the front thereof. It is not essential, of course, that these parts be of rubber, as will be evident from what I have stated. Along the back of the belt I form a flange as 13 which prevents the escape of pulp and 70 wash water from the belt, the flange extending the complete length of said belt, as shown clearly in Fig. 4. I have shown by arrows in Figs. 1 and 2 the direction of movement of the belt, and any suitable means 75 may be provided for operating the belt. I will herein-after briefly describe the means shown for this purpose. The connected beams 9 are oscillatory upon the shaft 6, this being for the purpose of angularly adjusting the belt, and for varying this angular adjustment I may provide duplicate devices acting against 80 the respective beams 9, one of which will now be described.

Upon the beam 4 shown in the foreground in Fig. 2 and carried by a suitable bearing thereon is a shaft as 14 having a cam as 15 operable by worm gearing 85 denoted in a general way by 16, the worm of said gearing being carried on the shaft 17 rotatably supported by bearings upon said beam 4 illustrated in said Fig. 2. Said shaft 17 is equipped with a hand wheel 18. By turning the two hand wheels, only one of which is 90 seen, I can, as will be clear, through the two cams 15 adjust the angular relation of the two beams 9 and thereby the endless concentrating belt 11. A worm gear is shown at 19, its shaft being supported by a bracket as 20 on the sill 2 shown in the foreground in 95 said Fig. 2. Upon the inner side of this worm gear 19 is a lug 21 co-operative with the lug 8 hereinbefore described. A worm 22 on the shaft 23 meshes with the worm gear 19, said shaft 23 being supported by the bracket 20 and by a bracket as 24 carried by the sill to which said bracket 20 is fastened. On the shaft 23 is shown a pulley 25 connected by a belt 26 with the pulley 27 on the main shaft 28 of the head motion denoted in a general way by 30. The head motion forms in itself no part of the invention, for which reason it is 105 unnecessary to describe the same in detail. Any suitable head motion may be employed so long as it gives to the endless belt an absolutely uniform accelerated forward stroke and a uniformly retarded rearward stroke. The forward or concentrating stroke of the belt, as will be clear, is transverse of the belt or in 110 a direction extending from the back to the front of the

belt, or, in other words, from the right towards the left in Fig. 3. In addition to such transverse stroke of the belt, which is given to it by the so called head motion 30, it has a traveling movement which is effected in 5 the present instance by the worm 22 and the worm gear 19, the worm receiving its motion from the shaft 28 through operative connections therewith. Owing to the two lugs 21 and 8 to which I have hereinbefore referred, there will always be an operative connection 10 between the worm gear 21 and the disk or wheel 7 so that, even while the belt is being vibrated or reciprocated through the head motion, it is also being simultaneously given its feeding movement. The upper run of the belt 11 is supported by several rollers as 31 15 carried by the connected beams 9. Owing to the presence of these rollers 31 there is no possibility of the upper run of the belt sagging between the rollers or drums 5 and 10 respectively.

The pulp is supplied on to the concentrating belt in 20 any way, for example, by a feed box as 32 shown conventionally in Figs. 2 and 3 and located substantially centrally of the belt 11 at the back thereof. I provide two pipes as 33 at opposite sides of the feed box 32 for supplying wash water, said pipes extending longitudinally of the belt at the back thereof also as indicated in said Figs. 2 and 3. The pipes may be supplied with the necessary wash water by pipes as 34. I have shown the wash water pipes 33 conventionally. The liquid slimes are discharged over the highest end of 25 the belt, while the tailings pass from off the lowest end of said belt, the heavier particles of the liquid slimes passing from the belt near the back thereof, while the heavier tailings are discharged from the opposite end of the belt near the front thereof. The values are discharged from the front of the belt and, for properly directing the same therefrom, I provide a discharge apron as 35 fitting under the front portion of the belt between the rollers 5 and 10 and carried by the forward beam 9, as shown clearly in Fig. 3. Under the 30 upper inclined portion of the belt 11 and between the sills 2 I prefer to arrange a tank as 36 to receive the slimes which may adhere to the belt after the drum 10 is passed and, for washing these adhering slimes from said belt, I provide a wash water pipe as 37 which directs a jet or jets of water against the belt to separate 35 therefrom any slimes which may adhere thereto, the slimes thus separated from the belt falling in the tank 36.

It will be assumed that the pulp contains galena, 50 iron, and zinc. Of course, pulp of any suitable kind may be delivered into the belt, but I have selected for illustration pulp containing these constituents to indicate the action of the apparatus. The pulp is supplied to the central back portion of the belt 11 from the feed box 32. The vibratory motion given to the belt by the head motion stratifies the pulp or causes the mineral values to settle in the spaces between the riffles 12. The wash water is, of course, flowing and aids in keeping the particles in suspension between the riffles. 55 Such wash water, however, is used primarily to wash the light or worthless material over said riffles 12, but has no direct effect in discharging the concentrates or mineral values over the front of the belt. The discharge of the concentrates is caused by the vibratory 60 motion, the material on each forward stroke of the belt

being moved from the back or feed side toward the front side. As the vibratory stroke has the least effect on the heavier materials such materials are discharged nearest the upper front side of the belt, while the lighter materials are discharged toward the lower front side of said 70 belt. Galena would be discharged near the extreme upper end of the belt, while iron and zinc would be discharged successively over the front side but between the galena and the lowest end of the belt. The quartz mixed with small mineral values is discharged at the 75 front of the belt near the lowest end thereof and is subsequently crushed to separate the mineral values therefrom and returned to the apparatus. The slimes stick more or less to the belt and cannot be readily discharged therefrom. They are therefore carried up with 80 the belt and fall from the same at the highest point thereof. The slimes which are not thus separated from the belt are washed therefrom into the tank or box 36 by water from the pipe 37. The heavier slimes are discharged from the belt near the back thereof, while the 85 lighter slimes leave the belt near the front thereof, but all at the extreme upper inclined end thereof. The tailings are discharged at the lowest end of the belt, the lighter tailings leaving the belt near the back, while the heavier tailings pass from the belt near the front thereof. 90

The beams or frame members 4, whether there be two or more, constitute a main vibratory frame while the connected beams 9 constitute an auxiliary frame. The auxiliary frame vibrates with the main frame, but is also oscillatory with respect thereto so as to vary the 95 angular relation of the concentrating belt.

What I claim is:

1. In an apparatus of the class described, an endless traveling transversely vibratory belt upwardly inclined from one end toward the other and adapted to discharge mineral values from each end, the belt having transversely-disposed riffles on the outer side thereof of progressively decreasing thickness from the back toward the front thereof, a feed-box at the back of the belt between the ends thereof, and wash-water pipes extending longitudinally of the feed-box, said belt serving on its vibratory movement to discharge mineral values from the front thereof. 100

2. In an apparatus of the class described, an endless traveling transversely vibratory belt upwardly inclined from one end toward the other and adapted to discharge mineral values from each end, the belt having transversely-disposed riffles on the outer side thereof of progressively decreasing thickness from the back toward the front thereof, a feed-box at the back of the belt between the ends thereof, wash-water pipes extending longitudinally of the feed-box, said belt serving on its vibratory movement to discharge mineral values from the front thereof, a tank under one end of the belt, and a pipe for washing slimes from the belt into said tank. 110

3. In an apparatus of the class described, an endless traveling transversely-vibratory belt upwardly inclined from one end toward the other and adapted to discharge mineral values from each end, the belt having transversely-disposed riffles on the outer side thereof of progressively decreasing thickness from the back toward the front thereof and adapted on said transverse vibratory movement to discharge mineral values from said front. 120

4. In an apparatus of the class described, an endless traveling transversely-vibratory belt upwardly inclined from one end toward the other and adapted to discharge mineral values from each end, the belt having transversely-disposed riffles on the outer side thereof of progressively decreasing thickness from the back toward the front thereof and adapted on said transverse vibratory movement to discharge mineral values from said front, and means for 130 washing slimes from the under side of the belt. 135

5. In an apparatus of the class described, an endless traveling transversely-vibratory belt upwardly inclined from one end toward the other and adapted to discharge mineral values from each end, the belt having transversely disposed riffles on the outer side thereof and being adapted to discharge mineral values over its front on its transverse vibration.

6. In an apparatus of the class described, an endless traveling transversely-vibratory belt upwardly inclined from one end toward the other and adapted to discharge mineral values from each end, the belt having transversely

disposed riffles on the outer side thereof and being adapted to discharge mineral values over its front on its transverse vibration, said belt also having a flange at the rear outer side thereof and extending throughout the complete extent 15 of said belt.

In testimony whereof I have hereunto set my hand in presence of two subscribing witnesses.

ABEL GUIONNEAU.
